CLAIM

The ornamental design for a shoe, as shown and described.

DESCRIPTION

FIG. 1 is a photographic front perspective view of a shoe showing my new design;

FIG. 2 is a top view thereof; and,

FIG. 3 is an enlarged view of the claimed portion as shown in FIG. 2 with environment removed for clarity purposes. The washed-out lighter grey portions are for the purpose of illustrating portions of the shoe which form no part of the claimed design. The broken lines immediately adjacent to and surrounding the dark grey photographic area represent the bounds of the claimed design and form no part thereof.
